UNITED STATES PATENT OFFICE.

WHEELER R. COLLINS, OF DENVER, COLORADO.

BILL-FILE.

SPECIFICATION forming part of Letters Patent No. 565,871, dated August 11, 1896.

Application filed January 13, 1896. Serial No. 575,404. (No model.)

To all whom it may concern:

Be it known that I, WHEELER R. COLLINS, a citizen of the United States of America, residing at Denver, in the county of Arapahoe and State of Colorado, have invented certain new and useful Improvements in Bill-Files; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in bill-files; and it consists of the features hereinafter described and claimed, all of which will be fully understood by reference to the accompanying drawings, in which is illustrated an embodiment thereof.

In the drawings, Figure 1 is a front elevation of my improved bill-file, one of the clasps (the one on the right) being open while the other is closed. Fig. 2 is a section taken on 25 the line *xx*, Fig. 1, looking toward the left. Fig. 3 is a section taken on the same line, looking toward the right.

Similar reference-characters indicating corresponding parts in these views, let the number 30 5 designate the frame-plate, having an opening 6 formed in its upper portion. This opening is surrounded on the bottom and the two vertical sides by a grooved way 7. This way 7 is indicated by dotted lines in Fig. 1. 35 Its two vertical portions are open at the top to permit the insertion of a memorandum-card, a calendar, or a card containing any matter convenient for use in connection with a bill-file. The lower part of the frame 5 40 consists of a plate 5^a, to which are attached the clasps 8, each composed of a spring-base 8^a, having a brad 8^c, and the movable part 8^d, hinged to the part 8^a at 8^b. The part 8^d is provided with a bend 8^e, whereby when the 45 movable part is raised (see Fig. 3) the free extremity of the spring-base 8^a is raised, thus placing the spring under tension and temporarily locking the part 8^d in the open position.

The part 8^d is provided with an aperture 8^j to receive the brad 8^c when the clasp is closed. 50 The base of the clasp is secured to the plate 5^a by rivets 9, or other suitable fastening devices placed at the angle formed by the parts 8^a and 8^c.

The upper part of the frame is provided 55 with a projection 5^e, in which is formed an aperture 5^d, to allow the device to be hung on a nail or other suitable supporting device.

In using the device the movable parts 8^d are raised, as shown in Fig. 3, to permit the 60 placing of the bills on the brads 8^c. The parts 8^d are then thrown to the position shown in Fig. 2.

Having thus described my invention, what I claim is—

1. As an improved article of manufacture, the herein-described bill-file comprising the frame-plate having its upper portion apertured, said aperture being surrounded on three sides by a grooved way; and a clasp 70 attached to the lower part of the plate and comprising the spring-base 8^a, the brad 8^c and the movable part 8^d apertured to receive the brad 8^c, and hinged to the free extremity of the spring-base 8^a, the part 8^d being provided with a bend adjacent its hinged extremity, as and for the purpose set forth. 75

2. As an improved article of manufacture, the herein-described bill-file comprising the frame-plate having one or more clasps, each 80 clasp comprising the spring-base 8^a having a brad 8^c, said base being fastened to the plate at a point adjacent the angle formed by the base and the brad; and the movable part 8^d 85 apertured to receive the brad, said part 8^d being hinged to the free extremity of the spring-base, and provided with a bend adjacent its hinged extremity, as and for the purpose set forth.

In testimony whereof I affix my signature 90 in the presence of two witnesses.

WHEELER R. COLLINS.
